UNITED STATES PATENT OFFICE.

LEWIS S. WATRES, OF SCRANTON, PENNSYLVANIA, ASSIGNOR TO HULL MANUFACTURING COMPANY, OF SCRANTON, PENNSYLVANIA, A CORPORATION.

FEED-WATER CONTROLLER AND LOW-WATER ALARM FOR BOILERS.

1,050,185.

Specification of Letters Patent. Patented Jan. 14, 1913.

Application filed June 24, 1911. Serial No. 635,091.

To all whom it may concern:

Be it known that I, LEWIS S. WATRES, a citizen of the United States of America, residing in Scranton, county of Lackawanna, 5 State of Pennsylvania, United States of America, have invented a certain new and useful Improvement in Feed-Water Controllers and Low-Water Alarms for Boilers, of which the following is a specification.

10 The feed water controller and low water alarm for boilers forming the subject of this invention comprises a water column connected to and having communication with the steam and water spaces of the 15 boiler, two outlets from the steam space of the column, a float in the column, two valves actuated by the float, one adapted to admit steam by one of the outlets to a whistle to sound an alarm before the water in the 20 boiler becomes excessively high and also before it becomes excessively low, and the other one adapted to admit steam by the other outlet to the feed water valve controller, to close said valve when the water is 25 at the normal working level.

In the construction of the feed water controller or governor is embraced one of the essential features of this invention, viz., a diaphragm with a large range of movement 30 so as to quickly and adequately operate the feed water valve. To this end the diaphragm consists of a disk of elastic material, as india rubber, reinforced on its convex side by a metallic disk somewhat smaller 35 than the active part of the elastic disk, rigid at its peripheral portion but made expansible at its central portion by radial slits, so as to enable it to freely expand with the less rigid elastic disk and at the same 40 time to hold the elastic disk within its proper working confines.

Other features of the invention will be referred to in the following description of the drawings.

45 Figure 1 illustrates the complete apparatus attached to the side of a boiler. Fig. 2 is a vertical sectional view of the water column, showing the float and valves, etc.; Fig. 3 is a sectional view, taken at right 50 angles to Fig. 2, of the upper part of the water column: Fig. 4, a plan view of the diaphragm and its reinforcing disk: Fig.

5, a vertical sectional view of the feed water valve diaphragm governor: Fig. 6, a section of the water trap included in the steam pipe leading to the diaphragm: and Fig. 7 is a sectional view of the steam whistle valve and its operating lever.

The water column *a* is by pipe connections attached in the usual manner to a boiler *b*, 60 the openings *c* and *d*, Fig. 2, being the steam and water connections respectively. In the column *a* is located a float *e* having an upwardly extending angular frame *f* whose upper end is provided with a hollow guide 65 rod *g* fitted to slide freely in a pipe extension *h* on the cover of the column, and a rod *i* on the float embraced by guide *j* controls the lower end of the float. In the pipe extension *h* is a freely sliding rod *k* 70 having at its lower end a valve *l* and a cross-head with lugs *m* which are embraced by slots in the sides of the frame *f*. This valve *l* seats, by gravity, in a valve seat *n* in the lateral pipe extension *o* of conduit *p* extending downwardly from the cover *q* of the water column, and said valve is raised from 75 its seat by the lower ends of the slots of the frame *f* contacting with the lugs *m* when the float *e* is raised by the water in the boiler 80 and column slightly above the normal working level. Another steam opening is also provided in the cover *q* leading to a steam whistle *r*, and extending downwardly from this opening is a tube *s*, containing a spring 85 closed valve *t*, which normally cuts off the steam from the whistle. In guide slots in the lower end of the tube *s* is held a double acting lever *u*, through which the rod of the valve *t* passes; the lower end of said 90 rod having an adjustable nut *v* against which the lever *u* acts to open the valve *t*. When the free end of the lever *u* is depressed, its other end, by acting on the edge *w* of the tube becomes its fulcrum and the 95 whistle valve is opened, and when the free end of the lever is raised then it, by a point between its free end and the stem of the valve *t*, by acting on the edge *x* of the tube becomes its fulcrum and the valve is also 100 opened, see Fig. 7. These actions are brought about by lugs *y* and *z* on the frame *f*. The upper one *y* acts on the lever when the water level has fallen to a point calling

for a notice, by the whistle sounding, being given, as indicated by the position of the float in Fig. 2; this condition may be due to a lack of water supply or derangement 5 of the feed water apparatus. The lower one *z* acts on the lever *u* to raise its free end when the water level rises excessively above the normal working limit, which may be also due to inoperativeness or derange- 10 ment of the feed water supply apparatus, notice then also being given by the whistle.

The feed water pipe 1 is provided with a valve 2 of ordinary construction, normally held open, and also with a check valve 3. 15 Connected to the valve 2 by a frame 4 is the casing 5 of the operating diaphragm. This diaphragm is of a compound character, consisting of a disk 6 of a suitable elastic material, as rubber, to provide for a large 20 range of movement and a reinforcing disk 7 of a strong flexible material, as metal, placed above disk 6. The disk 6 is firmly clamped between flanges of the casing 5 and rests, when in normal inactive condition, 25 upon a plug 8, having a central bore and scored or cross-grooved on its top and seated in the lower part of the casing to which is connected a water trap 9 by a pipe 10. The upper end of the trap is connected by the 30 pipe 11 to the steam conduit *p* through the cover of the water column. The trap 9 has in its side, near its upper end, a small orifice 12 for the escape of water of condensation when it reaches this level, which 35 may be directed in its course, as desired, by a pipe 13. When steam is acting through the pipe 11 to operate the diaphragm a small but immaterial quantity will escape through the orifice 12. 40 The metal disk 7 practically covers the whole of the upper surface of the disk 6. It is rigid at its periphery but is made flexible toward and at its central portion by radial slits 14, 14 extending a short distance 45 from the periphery to a central opening. On the central part of the disk 7 rests a flanged plate 15 having a central stem 16 extending through a hole in and slightly above the top of the casing 5. A spring 17 50 surrounds the stem 16 and acts between the casing and the plate 15 to press the diaphragms down in normal inoperative position, the elastic diaphragm then resting on the top of the plug 8, the grooves of which 55 afford communication to the underside of the diaphragm of the operating fluid. The valve rod 18 of the feed water valve 2 axially coincides with the stem 16, a narrow space being between their adjacent ends, 60 when the valve is open. Provision is made for closing the valve, to cut off water from the boiler when there is no steam pressure or should any part of the steam controlling devices become deranged, by means of a suit- 65 able instrument, as for instance a wedge 19,

which, to be always available for use, may be connected to the apparatus by a chain 20.

The water column *a* may be provided with gage cocks 21 and a drainage cock 22.

Of course it will be understood that the compound diaphragm having a long range of movement, here described, has other applications than to operate a feed water controlling valve, as for instance, it may be used to control a water level alarm. 70 75

I claim:

1. In an apparatus of the character specified, a yieldable diaphragm, a casing in which the diaphragm is held, a rod actuated by the diaphragm and extending through the casing, a pipe connected to the casing for directing an operating fluid to the diaphragm, a water feed controlling valve having an operating stem axially in line with the diaphragm rod and spaced a short distance therefrom and means adapted to be inserted between the rod and stem and to move said stem when the diaphragm is in inoperative position. 80 85

2. In an apparatus of the character specified, a compound diaphragm comprising a readily yieldable elastic disk and a superposed flexible disk of hard material, a casing in which the diaphragm is held, a pipe connected to the casing for directing an operating fluid to the elastic disk side of the diaphragm, a controlling means actuated by the diaphragm, a water column attached to the steam and water spaces of a boiler and into the steam space of which the pipe extends, 95 a valve seat in the pipe located centrally in the column, a float in the column and a valve in axial line with and directly controlled by the float, and raised from the valve seat when the float approaches its 100 uppermost position. 105

3. In an apparatus of the character specified, a yieldable diaphragm, a casing in which the diaphragm is held, a rod actuated by the diaphragm and extending through the casing, a pipe connected to the casing for directing an operating fluid to the diaphragm, a water feed controlling valve having an operating stem axially in line with the diaphragm rod and spaced a short distance therefrom, means adapted to be inserted between the rod and stem and to move said stem when the diaphragm is in inoperative position, a water column attached to the steam and water spaces of a 110 115 boiler and into the steam space of which the pipe extends, a valve seat in the pipe, a float in the column, and a valve controlled by the float adapted to close said valve seat. 120

4. In an apparatus of the character specified, a water column, a boiler to the steam and water spaces of which the column is connected, a float in the column having an upwardly extending frame, a valve extending downwardly and having a stem fitted to 125 130

slide freely in the upper part of the frame, a guide for the upper part of the frame, a pipe extending into the steam spaces and having a valve seat centrally located relative to the float and adapted to co-act with the valve, means on the frame for raising the valve from the seat as the water in the column rises above the normal working level

and a feed water controller connected to the pipe.

10

In testimony whereof, I have hereunto subscribed my name.

LEWIS S. WATRES.
